TOY TELEPHONE

Filed April 28, 1930

UNITED STATES PATENT OFFICE

NORMAN W. HILL, OF EAST HAMPTON, CONNECTICUT, ASSIGNOR TO THE N. N. HILL
BRASS COMPANY, OF EAST HAMPTON, CONNECTICUT, A CORPORATION

TOY TELEPHONE

Application filed April 28, 1930. Serial No. 447,815.

This invention relates to an improvement in toy telephones and particularly to toy telephones of the "continental" type, the object of the invention being to produce an attractive toy in a simple form, so that it can be produced at a low cost for manufacture, and the invention consists in the construction as hereinafter described and particularly recited in the claims.

10 In the accompanying drawings:

Fig. 1 is a side view of a toy telephone constructed in accordance with my invention;

Fig. 2 is a front view of the same;

Fig. 3 is a front view with the ends of the 15 telephone-handle broken away and with the gong of the bell removed;

Fig. 4 is a sectional view on the line 4—4 of Fig. 2;

Fig. 5 is a perspective view of the base of 20 the bell, detached; and

Fig. 6 is a perspective view of the bell-operating rack, detached.

In carrying out my invention, I employ a base 10 of any suitable design, and mounted 25 on the base is an L-shaped post 11 preferably formed from sheet-metal. Attached to the face of the base, near its upper end, is the base 12 of a bell-mechanism of the ordinary bicycle type. Extending through the base, so as to be 30 guided thereby, is a rack-bar 13 formed on one side with teeth 14 to engage with one of the pinions of the bell-operating mechanism. The rack is also formed with a longitudinal slot 15 through which the central post 16 of 35 the bell-mechanism extends, and this rack is normally held in its raised position by a spring 17 which is engaged with the base 12 and with the rack.

Secured to the upper end of the rack is a 40 yoke 18 which receives the handle 19 of a telephone-instrument of the continental type having a transmitter 20 at one end and a receiver 21 at the other end, the receiver being 45 connected with the base by a flexible cord 22.

A downward movement of the yoke moves 50 the rack-bar 13 and causes the bell to sound, and this movement may be imparted by pressing down upon the handle of the telephone before it is removed from the yoke, or press-

ing down upon the yoke after the handle has been removed.

By connecting the yoke directly with the bell-operating rack, a very simple construction is provided, and the yoke is suitably supported by the rack, which is guided for vertical movement through the base, the rack being long enough to extend entirely through the base so as to be vertically guided thereby.

I claim:

1. In a toy telephone-set, the combination with a base, of a bell-post uprising therefrom, a bell-unit secured to the post, a vertically-movable rack organized with the bell-unit for operating the same, and a telephone-receiver yoke secured directly to the upper end of the said rack and solely supported thereby and operating the same when depressed.

2. In a toy telephone-set, the combination with a base, of an L-shaped base-support having its horizontal lower arm secured directly to the base, a bell-unit rigidly mounted upon the upper end of the upright upper arm of the said bell-support, a vertically-movable rack mounted for vertical reciprocation in the base of the bell-unit and organized with the striking-mechanism thereof, and a horizontally-arranged telephone-receiver yoke mounted directly upon the projecting upper end of the rack.

In testimony whereof, I have signed this specification.

NORMAN W. HILL.
